UNITED STATES PATENT OFFICE.

PIOTR JARNUSZKIEWICZ, LUCJAN CHMIELOWSKI, STANISŁAW SZCZESNY, AND LUDWIK CHYBCZYŃSKI, OF WARSAW, RUSSIA, ASSIGNORS TO THE FIRM OF PIOTR JARNUSZKIEWICZ & CO., OF WARSAW, RUSSIA.

DISCONNECTIBLE METAL BEDSTEAD.

1,162,365.

Specification of Letters Patent. Patented Nov. 30, 1915.

Application filed January 20, 1914. Serial No. 813,170.

To all whom it may concern:

Be it known that we, PIOTR JARNUSZKIEWICZ, LUCJAN CHMIELOWSKI, STANISŁAW SZCZESNY, LUDWIK CHYBCZYŃSKI, subjects of the Czar of Russia, and residing at Warsaw, Russia, have invented certain new and useful Improvements in Disconnectible Metal Bedsteads, of which the following is a specification.

10 Our invention relates to disconnectible metal bedsteads.

Bedsteads which cannot be taken to pieces and each of whose sides comprises two tubes which are integral with the front and rear 15 ends of the bedstead are well known. In metal bedsteads which can be taken to pieces, however, it is very difficult to connect these sides, which are formed of two tubes or rods of various section, in a dust-tight manner 20 and without slots, to the other parts of the bedstead. When each side consists of only one rod, it has been attempted to make a suitable joint by specially shaped castings, but this has the disadvantage, on one hand, 25 that the weight and cost of the bedstead are considerably increased and, on the other hand that, in spite of the use of these castings, a rigid connection cannot be obtained.

30 A primary object of our invention is to obviate these defects. To this end, we provide a bedstead in which the sides, each of which comprises two rods, preferably tubes, are attached to the front and rear ends of the bedstead by means of cross-pieces which 35 carry short tubular members. These tubular members are connected in a dust-tight manner and without the use of slots, by means of tubular nuts, and screws welded to the outside tubes of the ends of the bedstead. The 40 employment of specially designed castings and the like is thereby completely obviated, the tubes at the end of the bedstead do not require to be drilled, nevertheless the individual parts are attached in a dust-tight 45 manner and without the use of slots.

One illustrative embodiment of our invention and a modification thereof is represented by way of example in the accompanying drawing, wherein:—

50 Figure 1 is a perspective view showing a preferred form of our improved bedstead, and Fig. 2 is an elevation showing the con-

nection of one side with one end; Fig. 3 is like view of a modified form of connection; Fig. 4 shows a key.

55

Referring to the drawing, the front and rear ends of the bedstead comprise the supports or feet 1 which are braced by stays 2. A cross-bar 3, which may be curved, is welded, preferably autogenously, at the height of 60 the mattress to the members 1 and 2 and is provided with holes into which the hooks of the mattress take. In addition, screw-bolts 5 are welded to the members 1. Each side of the bedstead comprises two tubes 6 which 65 are stiffened in the middle, preferably by one cross-member 7, and are connected one with another at the ends by connecting members 8. These connecting members 8 may be either rectilinear (Fig. 3) or curved (Fig. 70 2). Each connecting member has two tubular branches 9 for surrounding the bolts 5. Tubular nuts 10 are screwed on the bolts 5 in the branches 9 by means of the key shown in Fig. 4 so that the sides are connected 75 dust-tight and without slots with the ends of the bedstead. In this embodiment, the nuts enter the tubular members. In this manner the described disadvantages of known bedsteads are completely obviated, 80 because owing to the described dust-tight connection of the individual parts of the bedstead with one another, dust and the like cannot collect at the places of junction.

85

We have shown a preferred embodiment 90 of our invention, but it is obvious that changes can be made in the details thereof without departing from the spirit, as set forth in the following claims.

95 We claim:

1. In a disconnectible bedstead the combination with a vertical end support, of two screws welded thereon, a side rail for the bedstead comprising two rods and a transverse member connecting the ends of said rods, said transverse member having tubular members at the ends thereof normally surrounding said screws, and tubular nuts normally screwed on said screws and entering into said tubular members.

100

2. In a disconnectible bedstead, the combination of an end piece, a side rail normally attached to said end-piece, projections on said end-piece, and tubular members at the

ends of the said rail adapted to surround said projections and coact therewith, and a fastening means adapted to be mounted on each of said projections and to close the open 5 ends of the said tubular members.

3. In a disconnectible bedstead, the combination of an end piece, a side rail normally attached to said end-piece, projections on said end piece, and tubular members at the 10 ends of the side rail adapted to surround said projections and coact therewith, and a fastening means adapted to be mounted on each of said projections and to close the open ends of the said tubular members, the

said tubular members closely fitting on the 15 projections of said end piece.

In testimony, that we claim the foregoing as our invention, we have signed our names in presence of two subscribing witnesses.
